UNITED STATES PATENT OFFICE.

GEORGE W. WILMOT, OF HAZLETON, PENNSYLVANIA, ASSIGNOR TO WILMOT ENGINEERING COMPANY, OF HAZLETON, PENNSYLVANIA, A CORPORATION OF PENNSYLVANIA.

APPARATUS FOR WASHING COAL AND ORE.

Application filed May 10, 1922. Serial No. 559,793.

My invention relates to apparatus designed primarily for use in the washing of coal, but is also well adapted for use in the washing of ores of various and different kinds. More specifically stated, the invention relates to an apparatus of a continuously operating type in which the mixture of coal and slate and other material to be eliminated or of ore and dirt and other material to be eliminated from the ore mixture is caused to travel in the form of a column, preferably of small depth or thickness as compared with its width, across a constantly flowing stream of fluid, preferably water.

The principal object of the invention is to provide a novel construction of apparatus which is efficient in operation and which is particularly well adapted for use in the washing of coal of all commercial sizes.

A further object of the invention is to provide a novel construction of means for conveying the mixture of coal and slate and other matter or a mixture of ore with matter to be removed therefrom, in the form of a column as above indicated, through a body of water and simultaneously causing a portion of the said water to flow as a stream through and transversely of the said column. The coal, for instance, being of less specific gravity than the slate, dirt or other impurity mixed therewith, it follows that its movement through the said body of water is affected by the said stream to a greater extent than the heavier material consisting of the impurities, such as slate, so that a separation is brought about. The coal is lifted or carried upwardly or out of the mixture and is ultimately discharged from the apparatus separate from the slate and other material from which it is desired to separate the same.

Other objects and advantages of the invention will be pointed out in the detailed description thereof which follows or will be apparent from such description.

For the purpose of facilitating an understanding of the invention and in order that its practical advantages may be better appreciated, reference should be had to the accompanying drawings in which certain forms of mechanical embodiment thereof are shown. However, it will be understood that changes in the details of construction may

be made within the scope of the claims without departing from the principle of the invention.

In the drawings:

Fig. 1 is a view in vertical longitudinal section of an apparatus embodying my invention;

Fig. 2 is a top plan view of a portion thereof;

Fig. 3 is a vertical longitudinal section of a portion thereof, somewhat enlarged, showing a detail of the construction;

Fig. 4 is a vertical longitudinal sectional view showing a modified construction of the apparatus;

Fig. 5 is a top plan view of the same;

Fig. 6 is a transverse sectional view of a portion of the apparatus showing more clearly a detail of construction;

Fig. 7 is a vertical longitudinal sectional view showing another modified construction of the apparatus;

Fig. 8 is a transverse sectional view taken on the line 8—8 of Fig. 7; and

Fig. 9 is a top plan view of a portion of the said apparatus.

Referring to the drawings: 1 designates a tank which is adapted to hold the water which is employed in the washing of the coal or other material. The bottom of the tank is provided with a valve controlled opening at 2 of any known construction through which sludge is adapted to be discharged or removed from the tank. The coal, after it has been washed, is removed and discharged from the apparatus by means of the flights or buckets 3 upon the endless chain or conveyer 4, while the slate and other refuse material are conveyed and discharged from the apparatus by the flights or buckets 6 upon the endless chain or conveyer 7. The flights or buckets 3 operate in a trough 8, while the flights or buckets 6 operate in a trough 9.

Referring now to Figs. 1 to 3, inclusive, 10 designates a hopper from which the material, such as a mixture of coal, slate, etc., is delivered to an endless conveyer 11 having perforations 12 therein which conveyer is supported within the body of water with in the tank 1 by means of supporting drums 13, 14, 15 and 16 arranged in the manner indicated in Fig. 1. The feed or delivery of the material from the hopper 10 is regu-

lated by the feed control device 18. By this device the material is fed onto the horizontal portion of the conveyer 12 intermediate the two uppermost supporting drums 13 and 14. The drum 15 is located underneath and a considerable distance from the drum 14 while the drum 16 is located in a plane still lower than that in which the drum 15 is located, and a relatively great distance to the left thereof and also a relatively great distance to the left of the upper drum 13 whereby a section or portion of the conveyer 11 between the drums 13 and 16 is inclined downwardly at a considerable angle as shown.

For the purpose of causing traveling movement of the conveyer 11 in the direction of the arrow 21 in Fig. 3 I have provided that the drum 16 may be driven. For the purpose of driving the said drum I have provided a driving wheel 25 upon one end of the shaft 26 upon which the said drum is supported. The means for driving the said wheel 25 is not shown.

Rotation of the shaft 26 with the drum 16 thereon causes traveling movement of the conveyer 12 which in turn causes rotation of the drums 13, 14 and 15 and the shafts upon which they are supported, the said shafts being journaled in bearings upon the opposite sides of the tank.

For the purpose of causing a portion of the water within the tank 1 to flow transversely through the inclined section or portion of the conveyer 11 between the drums 13 and 16, I have provided a casing 30 which is substantially rectangular in cross section. The said casing 30 is situated within the body of water within the tank 1 and also within the space surrounded by the conveyer 11 and is supported by the cross bars 30'. The said casing constitutes a channel through which the water is caused to flow, as will be hereinafter described, and one end thereof is situated adjacent and in parallel relation to the under side of the inclined portion of the conveyer 11 between the supporting drums 13 and 16. The opposite or outer end of the casing 30 is flared, as indicated at 31, and situated within the said flared end portion are propellers 33. These propellers are mounted upon shafts 34 having at their outer ends beveled gears 35 which are in engagement with beveled gears 36 upon a shaft 37 journaled in the opposite sides of the tank 1. The said shaft is adapted to be driven from the shaft 26 by means of a transmission belt 38 upon the wheels 39 and 40, the first being secured to the shaft 26 and the second being secured to the shaft 37. Rotation of the shaft 37 causes rotation of the propellers 33 and the rotation of the latter causes a stream of water to flow through the channel or conduit formed by the casing 30.

Situated within the discharge end portion of the casing 30 are adjustable control devices 45 for regulating and controlling the angle at which the water shall be discharged from the casing. The control devices, which are in the form of plates, are pivotally supported at their opposite ends in the opposite sides of the casing 30. For the purpose of adjusting these control devices upon their pivots I have provided the bar 46 which is connected to the lower or inner edges of each of the said controlling devices 45, as is clearly shown in Fig. 3 of the drawings. The upper end portion of the said bar extends through an opening 47 in the top of the casing 30 which is substantially larger than the bar 46 so that the latter may have more or less play therein. The upper end of the bar 46 is connected to the lower end of an operating lever 48 pivoted intermediate its ends at 49 to the adjacent side of the tank 1. The upper end of the lever 48 terminates in a handle portion to facilitate the operation thereof. By turning the said lever about its pivot the bar 46 is actuated to change the angular position of the controlling devices 45 with respect to the channel of the casing 30. In Fig. 3 the control devices are shown in full lines at an angle of approximately forty-five degrees to a horizontal plane, in which position they extend transversely of the channel through the said casing and in dotted lines the said devices are shown in horizontal positions in parallel relation to the said channel. When in the full line position shown in Fig. 3 the said controlling devices cause the water, which is streaming through the channel of the casing 30, to be discharged from the said channel in a direction normal to the adjacent inclined portion of the conveyer 11. By varying the positions of the said controlling devices so as to vary the angles thereof with respect to the said conveyer the effect of the water as it flows through the openings 12 in the said conveyer upon the coal, which is being conveyed downwardly upon the inclined portion of the said conveyer, is varied. When the control devices are in the positions as shown in full lines in Fig. 3 the effect of the water upon the material traveling downwardly upon the adjacent portion of the conveyer is at its maximum. As the said devices are turned from their full line positions toward the positions indicated in dotted lines the effect upon the said material is slightly decreased so that the extent of the lifting or outward projection of the coal, which is the lighter portion of the material, is decreased.

The coal being of less specific gravity than the slate, dirt, etc., it passes outside of the shield or plate 50 and slides down into the lower end of the trough 8 and is carried by the flights 3 upwardly in said trough and

discharged at the upper end thereof into a chute or other means (not shown) which conveys the same to the desired point or destination outside of the apparatus.

5 The slate and other relatively heavy material continue their downward movement upon the conveyer between the plate 50 and the said conveyer and are discharged into the tank from which they are removed by 10 means of the flights or buckets 6 upon the conveyer 7, which operate in the trough 9.

Referring now to Figs. 4 to 6 inclusive, 60 designates a hopper for supplying the mixture of coal, slate and dirt or other material 15 to the apparatus to be washed. The hopper 60 is provided with an opening at its lower end through which the material is discharged onto a platform 61 from which it is removed by a plunger 62 which is operated by a connecting rod 63 having connection at its outer end to a rotatable crank disk 64. The plunger 62 effects movement of the material from the platform 61 onto the downwardly inclined delivery chute 65 from which the said material passes onto the horizontal portion 20 of the conveyer 11^a which is provided with the perforations 12^a. The said conveyer is supported upon drums 68, 69 and 70 arranged in triangular relation with respect 25 to each other. The said drums are supported upon shafts which are journaled at their opposite ends in bearings upon the opposite sides of the tank 1. The drums 68 and 69 are situated in the same horizontal plane 30 while the drum 70 is situated in a plane a considerable distance below that in which the drums 68 and 69 are situated and at a point corresponding to the apex of an isosceles triangle, the upper horizontal portion of the 35 belt constituting the base of said triangle.

The conveyer 11^a is driven by means of the drum 68 which in turn is driven by means of a driving wheel 71 (the means for driving the latter not being shown) upon the shaft 45 72 upon which the drum 68 is supported. The material to be washed is carried forward from its point of delivery upon the horizontal portion of the conveyer 11^a and the material of less specific gravity, as for 50 instance coal, is separated from the heavier material, such as slate, stone or the like, by the instrumentalities which will now be described.

Within the triangular space inclosed by 55 the conveyer 11^a the casing 75 of the shape of an inverted frustum of a pyramid is placed, the upper open end of which is situated in adjacent parallel relation to the under side of the horizontal portion of the 60 said conveyer. The lower end of said frustum is open, as clearly shown in Fig. 4. For the purpose of causing an upward flow 65 of water through the said frustum I have provided a propeller 76 which is situated adjacent to or within the opening in the lower

end of the said frustum, which propeller when rotated propels the water in a stream upwardly through the said frustum and through the perforations in the horizontal portion of the said conveyer. The propeller 76 is secured to the upper end of a vertical shaft 77 which is journaled in bearings 78 supported upon cross-bars 78^a. The lower end of the said shaft is provided with a beveled gear 79 which is in engagement with 75 a beveled gear 80 upon a shaft 81 which is journaled in the bearings upon opposite sides of the tank 1. One end of the said shaft 81 projects beyond one of the sides of the said tank and is provided with a wheel 82 over 80 which a driving band 83 extends, which band also extends over a wheel 84 upon the shaft 72 so that upon the driving of the latter the shaft 81 is driven which in turn operates to 85 actuate the propeller 76.

In order to control or regulate the angle at which the water as it issues from the top of the frustum 75 strikes the horizontal portion of the conveyer 11^a I have provided the regulating or controlling devices 85. These 90 devices consist of plates which are pivoted at their opposite ends in the opposite side walls of the frustum 75. In order to simultaneously actuate these devices and vary their angular position with respect to the horizontal portion of the conveyer 11^a between the drums 68 and 69, I have provided a bar 86 which extends transversely of the said controlling and regulating plates 85 and is secured to the lower edges 95 thereof as indicated at 87. The outer end of the said bar 86 projects through an end wall of the frustum 75 and is connected to the lower end of an operating lever 88 which is pivoted intermediate its 100 ends at 89 to the top frame member of the adjacent side of the tank 1. By actuating the lever 88 the angular positions of the regulating and controlling devices 85 with respect to the horizontal portion of the conveyer 11^a may be varied to thereby vary the 105 angle at which the streams of water issuing from between the said controlling devices strike or impinge upon the said horizontal portion to thereby vary the effect of the 110 moving stream of water as it issues through the perforations 12^a of the said horizontal portion of the conveyer upon the material being treated. The portion of the material 115 of less specific gravity, such as the coal, will be elevated and separated from the heavier portions thereof, such as slate, etc., and ultimately will be conveyed onto the top of the 120 plate 90 which is adapted to be adjusted vertically by means of adjustable rods 91, one of 125 which is shown in Fig. 4. The coal is discharged from the said plate 90 into the trough 8 and is conveyed by the flights 3 which move in the direction indicated by the 130 arrows in Fig. 4 upwardly in the trough 8

from which it is discharged into a chute, a portion of which is indicated at 92. The impurities which may consist of slate, stone and the like are of greater specific gravity than the coal and in consequence are carried along upon the conveyer 11^a and discharged underneath the plate 90.

For the purpose of returning the water from the trough 8 back into the tank 1, I 10 have provided a return pipe 93, the upper end of which is situated underneath the perforated upper end portions of the bottom of the trough 8 and the chute 92.

In the construction as shown in Figs. 7 to 15 9 inclusive, the material consisting of a mixture of coal, slate, etc., or of ore, dirt, etc., is discharged from a hopper 10^a on to the horizontal portion of a conveyer 11^b. The discharge of the material is controlled by 20 the controlling device 18^a. The hopper 10^a and controlling device 18^a are identical with the parts designated 10 and 18 of Fig. 1.

The conveyer 11^b is supported upon drums 13^a, 14^a, 15^a and 16^a corresponding to the 25 drums 13 to 16 inclusive shown in Fig. 1 of the drawings.

Situated within the space surrounded by the conveyer 11^b is a casing 30^a similar to the casing 30 shown in Fig. 1 and occupying the same position with respect to the conveyer 11^b and performing the same function as the said casing 30. The said casing 30^a is supported by the cross-bars 30^b corresponding to the cross-bars 30' in Fig. 1. 35 Situated in the forward or discharge end of the channel of the casing 30^a are control devices 45^a which are adapted to be adjusted for regulating and controlling the direction of delivery of a stream of water which may 40 be caused to flow through the channel of the casing 30^a. For the purpose of adjusting the said devices 45^a I have provided a bar 46^a which is connected to the lower edges of said devices and which extends upwardly 45 through the top side of the casing 30^a. The upper end of the said bar is connected to the lower end of an operating lever 48^a pivoted at 49^a to a side of the tank 1. The outer or right-hand end of the casing 30^a 50 is flared as is clearly indicated in Figs. 7 and 9 of the drawings.

For the purpose of causing the water to flow as a stream through the channel of the casing 30^a, I have provided propellers 95 which are mounted upon the inner ends of shafts 96 supported adjacent their inner ends in bearings 97 upon a cross bar 98. The outer ends of the said shafts are journaled in bearings upon the front end of the tank 1.

For the purpose of further agitating the water within the tank and causing the same to flow toward the right underneath the casing 30^a I have provided the additional propellers 100 which are mounted upon the inner ends of shafts 101, the inner end por-

tions of which are journaled in bearings 102 upon a cross bar 103. The outer ends of these shafts are mounted in bearings upon the front end of the tank 1.

As an additional agitating means, I have 70 provided a propeller 105 situated adjacent the bottom of the tank 1 and supported upon the inner end of a shaft 106 journaled in bearings 107 which are supported upon the front end of the tank adjacent its lower 75 edge. The said propeller is situated adjacent the said front end of the tank and is adapted to drive the water forward against the deflectors 108, which extend upwardly 80 and forwardly and are connected at their upper ends to cross bars 109 which extend transversely of the bottom portion of the tank and are secured to the opposite sides thereof. The lower ends of the said deflectors terminate near the bottom of the 85 tank. The said deflectors are spaced from each other and increase in length from the front toward the rear and provide upwardly 90 extending passages to cause an upward deflection and flow of the water toward the bottom, slightly inclined section of the conveyer 11^b between the drums 13^a and 16^a.

The agitation of the water by means of the propeller-agitators 100 and 105 is particularly desirable in case of the addition of 95 sand or other material to the water as is now some times done in order to increase the specific gravity of the separating liquid,—the sand mixing with the water and acting therewith to effect separation of the lighter 100 material from the mixture.

The several shafts 96, 101 and 106 are provided with wheels or pulleys 110 upon their outer ends by means of which they may be driven. The means for driving 105 these wheels is not shown.

The presence of a plate 111 extending cross-wise of the tank, the lower edge of which terminates in contact with or adjacent the front edge of the first of the bars 109, 110 forms a more or less restricted passageway for conducting the water downwardly toward the propeller 105. The forward movement of the water underneath the conveyer 11^b is limited by the presence of the cross-wise extending breast or baffle plate 112.

In the use of the apparatus the mixture of coal and slate or other material is delivered onto the upper horizontal portion of the conveyer 11^b and is transported thereby toward the delivery end of the apparatus. As it travels downwardly upon the inclined portion of the conveyer between the drums 13^a and 16^a it is subjected to the influence of the stream or streams of water which issue from the channel of the casing 30^a and the lighter material, for instance coal, is lifted or moved away from the conveyer to such an extent that it passes outside of the breast plate 50^a corresponding to the similar 125

plate shown in Fig. 1. The said coal falls down into the trough 8 and is carried upwardly by the flights 3 of the conveyer 4 which travels in the direction of the arrows shown in Fig. 7 and is discharged from the said trough onto a suitable chute or other distributor by means of which it is conducted to any point desired. The slate, stone, dirt, etc., being heavier than the coal, 10 continue downwardly upon the inclined portion of the conveyer between the latter and the breast plate 50^a and are discharged onto the lower end of the conveyer comprising the flights 6 which travel in the direction indicated by the arrows in Fig. 7 and are discharged from the apparatus and distributed or conveyed to any point desired.

It will be apparent from the drawings that in the several forms of construction 20 shown the top level of the water within the tank 1 occupies a plane a sufficient distance above the column of the mixture of coal or ore and impurities to completely cover the same so that the flowing stream of water which strikes the said column effects separation of the coal or ore from the impurities which may be mixed and intermingles therewith within the body of the water in the tank at the point and within the region 25 where the said stream strikes the said column. The coal or ore being lighter than the impurities is buoyed upwardly within the water in the tank while the impurities which are heavier or of greater specific 30 gravity than the coal or ore are not so buoyed or lifted upwardly and consequently separation takes place.

In the several specific forms of construction as illustrated in the drawings the water 40 or washing fluid is discharged from the respective casings 30, 30^a and 75 and is divided into a plurality of wide but relatively thin streams which strike the adjacent portions of the conveyers. The streams are 45 projected or are caused to flow through the perforations in the said conveyers and are subdivided thereby into a plurality of relatively small streams which contact with the moving column of the mixture of coal and 50 impurities or ore and impurities. At such time the mixture constituting the said column is moving forward so that and in consequence of which the particles thereof are subjected to a succession of impacts; that 55 is, they are subjected successively to the said relatively small streams of water or other washing fluid.

In each of the forms of construction as 60 illustrated the coal or ore of less specific gravity is lifted or floated from the said column while the impurities of greater specific gravity remain upon the conveyer and are carried forward thereby away from the coal or ore.

While it is preferred to employ a plural-

ity of wide and relatively thin streams as described yet the number of these streams may be varied.

Having thus described my invention, what I claim and desire to secure by Letters 70 Patent is:

1. In a coal and ore washing apparatus, the combination of traveling means situated within a body of water for conveying coal or ore through the said body of water the 75 said coal or ore being adapted to be deposited upon said means, means also situated within the said body of water for creating a continuously flowing stream of water and causing the same to flow through the 80 said coal or ore as it is carried along by the said means, and means for varying the angle at which the said stream strikes the said coal or ore.

2. In a coal and ore washing apparatus, 85 the combination of an endless band conveyer, means for supporting said conveyer within a body of water, means for depositing coal or ore thereon to be washed, means for causing traveling movement of said conveyer to convey coal or ore to be washed through the said body of water, and means situated within the space encircled by the 90 said conveyer for creating and causing a stream of water to flow through a portion 95 of the said conveyer and through any coal or ore which may be supported upon said conveyer.

3. In coal and ore washing apparatus, the combination of a traveling endless conveyer 100 for conveying coal or ore through a body of water, the said conveyer having openings extending therethrough, means for supporting the said conveyer, a casing within the 105 said body of water in the space encircled by the said conveyer, both ends of said casing being open and one end thereof terminating adjacent the inner side of a portion of the said conveyer, and propelling means situated at the outer end of the said casing for forcing a continuously flowing stream of water through the said casing, and adjustable means situated adjacent the inner end of 110 said casing for regulating the direction of discharge of the water from the said casing 115 through successive openings in the said conveyer as the same travels past the adjacent end of said casing.

4. In apparatus of the character described, the combination of a tank adapted to contain water, an endless conveyer situated within the said tank for conveying the material to be washed through the water 120 therein, the said conveyer having openings therethrough, means for supplying material 125 to be washed to the said conveyer, means for causing traveling movement of said conveyer, a casing forming a conduit situated within the said tank in the space encircled by the said conveyer, the said casing consti- 130

tuting a conduit and one end thereof terminating adjacent and in parallel relation to a portion of the said conveyer, means for causing a continuously flowing stream of 5 water to pass through the conduit formed by said casing, and adjustable means situated within the said casing adjacent the under side of said conveyer for varying the angle at which the water as it issues from the 10 said conduit is discharged against the said conveyer.

5. In apparatus of the character described, the combination of a tank adapted to hold water, continuously moving means situated 15 in the upper portion of the tank for conveying a column of the material to be washed through the water in the said tank, means within the said tank and adjacent the said conveying means for creating and driving 20 a continuously flowing stream of water through the said means to effect washing and separation of the said material, and means situated in the lower portion of the tank for effecting the formation of a plurality of 25 streams and for directing the same upwardly toward the said conveying means, substantially as described.

6. In apparatus of the character described, the combination of a tank adapted to hold 30 water, continuously moving means within the upper portion of the said tank for conveying the material to be washed through the said water, means for creating and driv-

ing a continuously flowing stream of water through successive portions of said means 35 and through successive portions of the material to be washed to effect washing and separation thereof, a plurality of deflector plates situated adjacent the bottom of the tank, and means for creating and directing 40 a continuously flowing stream of water against the said deflector plates which deflect and direct the same toward the said conveying means, substantially as described.

7. In apparatus of the character described, 45 the combination of a traveling conveyer for conveying material to be washed through a body of water, means for supporting said conveyer within the said body of water, a casing open at both ends to form a channel 50 within said body of water, one end of said casing terminating adjacent the under side of a portion of said conveyer and the opposite end of said casing being flared, propelling means located within said flared end 55 for driving a stream of water through the said channel, and adjustable plates pivotally supported within the end of said casing adjacent the said conveyer, and manually operable means for adjusting the said plates 60 to vary the angle of discharge of the water from the said channel.

In testimony that I claim the foregoing as my invention, I have hereunto signed my name this 21st day of April, A. D., 1922.

GEORGE W. WILMOT.
